UNITED STATES PATENT OFFICE.

CLARK ORR, OF FORT WAYNE, INDIANA, ASSIGNOR TO GENERAL ELECTRIC COMPANY,
A CORPORATION OF NEW YORK.

EVAPORATOR.

Application filed June 29, 1920. Serial No. 392,668.

To all whom it may concern:

Be it known that I, CLARK ORR, a citizen of the United States, residing at Fort Wayne, county of Allen, State of Indiana, have invented certain new and useful Improvements in Evaporators, of which the following is a specification.

This invention relates to evaporators and more particularly to those which are provided with means for separating liquids of different specific gravities. Evaporators of this character may be incorporated in refrigerating systems of that type wherein the refrigerant in gaseous condition is compressed and cooled until it is liquified and then allowed to evaporate. The liquid refrigerant when it enters the evaporator is often mixed with lubricant from the compressor or other parts of the apparatus and my improved evaporator is adapted to separate the refrigerant from the lubricant and return the lubricant to the circulating system while the liquid refrigerant is retained in the evaporator as long as it remains a liquid.

Referring to the drawing, Fig. 1 is a section of one form of evaporator embodying my invention; Fig. 2 is a sectional view partly diagrammatic of a refrigerating system employing a modified form of evaporator; and Fig. 3 is a section showing a still further modification.

In the form shown in Fig. 1, my evaporator comprises two dish-shaped members 10 and 11, secured together at their edges and forming an evaporating chamber 12. An inlet pipe 13 communicates with the evaporating chamber through bushing 14, secured in the top of the member 10 and pipe 15 secured to the bushing 16 at the bottom of the chamber serves as an outlet. Bushing 16 is extended a predetermined distance into the chamber 12 and has secured thereto by the means of brackets 17 a baffle plate 18.

When the evaporator is used in a refrigerating system the mixture of liquid refrigerant and lubricant enters the evaporator through pipe 13, flows over the baffle plate 18 and collects in the bottom of the chamber 12. The lubricant, being lighter than the refrigerant, rises to the top and ultimately overflows the bushing 16 and is returned to the compressor. The space between the bushing 16 and bottom of the

chamber is so dimensioned that it will hold all of the liquid refrigerant used in the system. The result is therefore that all liquid refrigerant entering the chamber 12 remains therein until entirely evaporated. The baffle plate 18 serves to divert the entering stream of refrigerant from the outlet opening and to spread it over a large surface to facilitate its evaporation. The shape of the evaporating receptacle is such as to form a large cooling surface.

In Fig. 2 the evaporator is composed of a plurality of chambers to provide a still greater cooling surface. The chambers are connected by nipples or bushings 19 which together with the bushing 20 project some distance above the bottoms of the chambers and form a storage space for holding a substantial part of the liquid refrigerant of the system. This provides a combined storage space of a capacity equal to the entire volume of liquid refrigerant used in the system. The baffle plates 18 are supported upon brackets 21 which rest upon the lower dish-shaped members 22. In Fig. 2 I have shown the evaporator connected with the compressor and condenser 26 of a refrigerating system. While the evaporator is shown at one side of the compressor and condenser, it will be understood that the same may be located beneath the compressor and condenser such as where for example it may be desired to mount the compressor and condenser over an opening in the top of the refrigerator and the evaporator directly beneath the refrigerating compartment.

The form shown in Fig. 3 differs from that shown in Fig. 2 by the addition of collars 23 which are secured to and depend from the baffle plates 18. These collars surround and extend somewhat below the outlet openings and each is provided at its top with a cut-away portion 24. This form is adapted for use with lubricants which are heavier than the refrigerant. In operation the mixture collects in the lower part of the chambers, the heavier lubricant settling to the bottom and ultimately covering the lower edges of the collars 23. As the mixture continues to collect, the lubricant is forced to rise in the space between the collar and the outlet bushing by the hydrostatic pressure and finally overflows this bushing and passes into the next cham-

ber or into the outlet pipe 15. The vaporized refrigerant passes out of the chambers through the openings formed by the cut-away portions 24. By properly proportioning the parts, this form of my invention may be used in refrigerating systems which employ lubricants either of greater or less specific gravity than the refrigerant. In case a lighter lubricant is used, the openings formed by the cut-away portions 24 will serve as overflow openings.

It is obvious that the collars 23 may be connected to the outlet bushings instead of to the baffle plates or they may serve as a means for supporting the baffle plates.

What I claim as new and desire to secure by Letters Patent of the United States, is:—

1. In a refrigerating system, an evaporator comprising a casing having an inlet opening in the top thereof, an overflow outlet opening through the bottom thereof, and a baffle located within said casing between said openings, said casing and outlet opening being arranged to form a storage space within said casing beneath said outlet opening for holding a substantial part of the liquid refrigerant of said system.

2. In a refrigerating system, an evaporator comprising a casing formed of dish-shaped members secured together at their edges, said casing having an inlet opening in the top thereof, an overflow outlet opening through the bottom thereof, and a baffle within said casing located between said openings, said casing and outlet opening being arranged to form a storage space within said casing beneath said outlet open-

ing for holding a substantial part of the liquid refrigerant of said system.

3. In a refrigerating system, an evaporator comprising a casing, having an inlet opening, a hollow bushing having imperforated walls extending through the bottom of said casing and communicating with the interior of said casing at some distance above the bottom thereof and thereby forming a storage space for holding a substantial part of the liquid refrigerant of said system and a baffle plate located between said inlet opening and said bushing.

4. In an evaporator, a casing having an inlet at the top thereof, and a tubular outlet member extending through and opening some distance above the bottom thereof, a baffle plate supported from said casing and extending between said inlet and the opening of said tubular member and a collar secured to said plate, and surrounding and spaced from said tubular member, said collar being also spaced from the bottom of said casing and being provided at its upper end with a cut-away portion.

5. In a refrigerating system, an evaporator provided with an outlet passage extending upwardly into said evaporator and opening some distance above the bottom thereof and forming a storage space for holding a substantial part of the liquid refrigerant of said system, a collar surrounding said passage and having cut away portions communicating with said evaporator at a point above said opening.

In witness whereof, I have hereunto set my hand this 23rd day of June 1920.

CLARK ORR.
